UNITED STATES PATENT OFFICE.

CHARLES B. DE LANO, OF KALAMAZOO, MICHIGAN, ASSIGNOR TO KALAMAZOO STOVE COMPANY, OF KALAMAZOO, MICHIGAN.

CONDUIT.

1,284,064.

Specification of Letters Patent.

Patented Nov. 5, 1918.

Application filed April 5, 1918. Serial No. 226,821.

To all whom it may concern:

Be it known that I, CHARLES B. DE LANO, a citizen of the United States, residing at the city and county of Kalamazoo, State of Michigan, have invented certain new and useful Improvements in Conduits, of which the following is a specification.

This invention relates to improvements in conduits.

10 My improved conduit or pipe is especially designed by me for use as the cold air supply or return conduit for furnaces, although it is adaptable and desirable for use in many other relations.

15 The main objects of this invention are:

First, to provide an improved conduit or pipe formed from sheets of paper board or other fibrous material.

Second, to provide an improved conduit 20 which may be shipped in the knockdown and nested form and quickly set up and assembled for use on the job by an unskilled workman.

Third, to provide an improved conduit 25 having these advantages which is very simple and economical and at the same time highly satisfactory and durable in use.

Further objects, and objects relating to 30 structural details, will definitely appear from the detailed description to follow.

I accomplish the objects of my invention by the devices and means described in the following specification. The invention is clearly defined and pointed out in the claims.

35 A structure which is a preferred embodiment of my invention is clearly illustrated in the accompanying drawing, forming a part of this specification, in which:

Figure I is a perspective view of a section 40 of my improved conduit.

Fig. II is an enlarged detail section through the seam on a line corresponding to line 2—2 of Fig. I.

Fig. III is an enlarged detail section 45 through the seam on a line corresponding to line 3—3 of Fig. I.

Fig. IV is a perspective view of the sheet metal seam member.

Fig. V is a plan view of the blank from 50 which the clips are formed.

Fig. VI is a detail elevation of a conduit embodying my invention erected.

Fig. VII is a perspective view of a number 55 of the conduit bodies nested for shipment and storage.

In the drawing similar reference characters refer to similar parts throughout the several views, and the sectional views are taken looking in the direction of the little arrows at the ends of the section lines.

60 Referring to the drawing, the bodies 1 of the conduit members or sections are conformed from sheets of paper board. This may be done on bending rolls quite similar to those used for conforming sheet metal 65 conduits or pipes. I preferably provide each section with a circumferential bead 2 adjacent one end and with a reduced portion 3 at the outside of the bead adapted to be telescoped into a coacting section.

70 The sheet metal seam members 4 are folded longitudinally to provide oppositely facing superimposed channels 5 in which the longitudinal edges of the body are disposed in overlapping relation. The channels are 75 clamped upon these overlapped edges and preferably further retained by indenting the same at intervals, as 6. For additional security I provide clips 7 formed of sheet metal and having tongues or prongs 8 80 struck therefrom, the prongs being disposed through the body at the edges of the seam member and preferably clamped thereon as shown in Fig. III.

85 It is found quite satisfactory to provide these clips at the ends only as it is only at these points that the members are subjected to any substantial stress in handling and assembling. The conduit is quite satisfactory when these clips are omitted.

90 My improved conduit may be shipped and stored in the knockdown and nested form, as shown in Fig. VII, and the seam members easily applied by the workman, even an unskilled workman, at the place of erection.

95 My improved conduit is much more economical than metal or wood conduits, is light in weight and easily erected. While I have particularly designed and illustrated my improvements as I have adapted the 100 same for air conduits for furnaces, they are desirable for use in numerous other relations. I have not illustrated or described such adaptations and modifications which might be necessary for such other uses, as I 105 believe the disclosure made will enable those skilled in the art to which my invention relates to embody or adapt the same as may be desired.

110 Having thus described my invention, what

I claim as new and desire to secure by Letters Patent, is:

1. A conduit member comprising a body conformed from a sheet of paper board, a sheet metal seam member having superimposed oppositely disposed channels in which the longitudinal edges of the body are disposed in overlapping relation, the seam member being indented and clamped upon the body, and clips provided with prongs disposed through the body at the edges of the seam member and clamped thereon.
2. A conduit member comprising a body of fibrous material, a sheet metal seam member having superimposed oppositely disposed channels in which the longitudinal edges of the body are disposed in overlapping relation, the seam member being indented and clamped upon the body, and clips provided with prongs disposed through the body at the edges of the seam member and clamped thereon.
3. A conduit member comprising a body

of fibrous material, a sheet metal seam member having superimposed oppositely disposed channels in which the longitudinal edges of the body are disposed in overlapping relation, and clips provided with prongs disposed through the body at the edges of the seam member.

4. A conduit member comprising a body of fibrous material, a sheet metal seam member having oppositely disposed channels in which the longitudinal edges of the body are disposed in overlapping relation, and clips embracing the seam member and engaging the body member at the edges thereof.

In witness whereof I have hereunto set my hand and seal in the presence of two witnesses.

CHARLES B. DE LANO. [L.S.]
